DESIGN FOR A PERMANENT HAIR WAVING MACHINE OR SIMILAR ARTICLE

William A. V. Thomsen, Plainfield, N. J., and
Carl G. Gross, Mount Vernon, N. Y., assignors to
American Machine and Metals, Inc., New York,
N. Y., a corporation of Delaware

Application March 13, 1935, Serial No. 55,876

Term of patent 7 years

To all whom it may concern:

Be it known that we, William A. V. Thomsen
and Carl G. Gross, citizens of the United States
and residents of Plainfield, in the county of
Union and State of New Jersey, and of Mount
Vernon, in the county of Westchester and State
of New York, respectively, have invented a new,
original, and ornamental Design for Permanent
Hair Waving Machines or Similar Articles, of
which the following is a specification, reference

being to the accompanying drawing, forming part
thereof.

The figure is a perspective view of a permanent
hair waving machine.

We claim:—

The ornamental design for a permanent hair
waving machine or similar article as shown.

W. A. V. THOMSEN.
CARL G. GROSS.
